UNITED STATES PATENT OFFICE.

ALBERT J. RYAN, OF CINCINNATI, OHIO.

MACHINE FOR PRESSING IN BOX-TOES.

1,356,017.

Specification of Letters Patent. Patented Oct. 19, 1920.

Application filed June 10, 1916. Serial No. 102,981.

To all whom it may concern:

Be it known that I, ALBERT J. RYAN, a citizen of the United States, and a resident of the city of Cincinnati, in the county of 5 Hamilton and State of Ohio, have invented certain new and useful Improvements in Machines for Pressing in Box-Toes, of which the following is a full, clear, and exact description, reference being had to the 10 accompanying drawings, forming part of this specification.

My invention relates to that certain novel machine to be employed in the manufacture of shoes and which consists in mechanism 15 for pressing down of box toes together with the uppers of shoes immediately after tacking the upper to the last and inserting the box toe, and before wiping in the upper, and lasting the shoes.

20 The great difficulty with box toes in shoes particularly in the present style of shoes which have a smooth toe, without any added toe trim, such as has been the style in the past, is that the edge of the box shows in 25 the completed shoe in a ridge which is unsightly. Where an extra trim is sewed onto the upper, this may be arranged to conceal the ridge left by the box, but as above stated, it is no longer the universal practice to have 30 such a trim. Box toes become very hard after standing in the shoe when pulling over and tacking of the upper to the last is accomplished, and the wiping in of the upper in the present processes merely pulls 35 the upper around the edges of the last, and the only flattening down of the box toe that is accomplished is that which results from pulling the upper tightly down on the last. Leather is not strong enough to withstand a 40 pull that will completely smooth down the box toe, even if it is still soft, and moreover the pressing down of the box must be accomplished by a pressure medium that fully conforms to the shape of the last and has no 45 strain on the leather.

These objects I accomplish by that certain machine having a structure and arrangement of parts to be hereinafter more specifically pointed out and the invention herein 50 duly claimed.

In the drawings,

Figure 1 is a side elevation of the machine.

Fig. 2 is a top plan view thereof.

Fig. 3 is a front elevation of the pressure 55 devices thereof.

Fig. 4 is an enlarged detail, partly in section, of the pressure plunger.

Fig. 5 is a plan view of the canvas top that fits over the shoe of the plunger member.

60

Fig. 6 is a detail side elevation of one of the pivoted claws.

Fig. 7 is a perspective view of one of the shoe engaging clips that are pivoted to the 65 ends of the claws.

65

In the treatment of a shoe, in lasting of the same, one of the first assembling operations is to pull the upper over the last that is to be employed, and to tack it down with a number of tacks to the bottom of the last. 70 At this time the box toe, which consists of a piece of felt impregnated with gums and waxes that dry and become very hard, is inserted in place in the toe of the upper, in a softened condition.

75

The usual process in use in welt shoes at the present time has for the next step the wiping in of the upper, which is done by means of a machine which engages the upper at the edges of the last and draws it 80 tightly over the last inserting more tacks to hold it in place without any wrinkles at said edges. Now the boxes will show in a raised edge after this operation unless an operative with a hammer pounds down the 85 box, which is a slow and expensive operation that cannot be resorted to in the less expensive type of shoes, and is likely to result in ruining the shoe.

In my new machine after the pulling over 90 and tacking is done, I apply pressure to the upper side of the last by means of a yielding pressure device that conforms to the shape of the toe, and while the box is soft I iron it down against the last by applying this 95 pressure, thereby matting the upper and box together.

The use of my machine is also of great value in that as far as the toe is concerned, the lasting operations of the shoe beginning 100 with wiping in are rendered much easier. The leather parts over the shoe are held down firmly and remain smooth and flat. This is of great importance in the lasting of shoes, as it is with the toe that the largest 105 amount of difficulty is had.

The shoe is allowed to stand after this pressing is done, and the box becomes hard, without raising up during the hardening, as the applying of the pressure so com- 110

pletely mashes down the box that it will harden in its flattened condition and leave no apparent ridge in the upper of the completed shoe. It should be understood that 5 this operation must occur while the box is soft and after it is inserted in the upper and the upper pulled over the last. Moreover the pressure must be applied uniformly over the toe without pulling on the leather, by 10 a member that is flexible to conform to the toe.

The machine is mounted on a framework having legs 1, 1, and a top or table portion 2. A bracket 3 which serves as the support 15 for the pressing device, is mounted on the table, and has mounted between extensions 4, at its forward side, the rods 5, 5, one at each side. A cross head 6 is provided adapted to slide on these rods 5, 5, and connected directly to the cross head are rods 7 which are secured at their lower ends to a treadle 8 which is pivoted at the rear side of the frame near the base thereof. This treadle when depressed by the foot will 20 draw the cross head downwardly toward the table portion of the frame.

Mounted on the rods 5, 5, above the cross head, is another sliding bar 9, which has secured at its under side the shaft or plunger 30 10. The bar is connected to the cross head by means of rods 11, 11, at each end, and the plunger extends down through the middle of the cross head.

Pivottally mounted around a ring 12, 35 mounted on the under side of the cross head, and through which ring the plunger extends, are a series of preferably five claws 13, which form a half circle. These claws extend downwardly and have pivoted to 40 their ends the clips 14, preferably by a hinged connection 15.

The plunger 10 telescopes into a hollow shaft 10^a and is slidable therein as limited by a pin 16 on the plunger which engages 45 in a slot 17 in the hollow shaft. The hollow shaft is provided at its base with a rubber foot 18, and cemented to the bottom of the foot is a sheet of canvas 21, to the under surface of which is secured a sheet of rubber 20. This canvas with the rubber facing forms the pressure shoe by means of which the pressure is applied to the box toe. The canvas sheet and rubber are cut at the edges into a series of five scallops so as to leave 50 tabs 22, 22, which are engaged and held in the clips 14, by means of screws or rivets (not shown), or in any other desired manner.

When the treadle is depressed, supposing 60 that a last has been mounted beneath the pressure member, as will be described, the first movement downward will bring the cross head and plunger downwardly until the pressure shoe contacts with the upper 65 side of the toe of the last. Continued mo-

tion of the treadle forces the plunger down against the spring and forces the pressure shoe firmly against the top of the last and at the same time forces the claws around the sides of the last toe, and pulls down on the 70 pressure shoe. As soon as this pressure extends the rubber portion of the shoe to a safe extent, the force of the claws is expended on the canvas backing of the said pressure shoe, and the continued downward 75 movement tightly stretches the shoe over the toe of the last, the plunger sliding in the shaft so as to allow the continued downward movement.

Secured to the upper sliding bar 9 is a 80 cord which passes over sheaves at 23 and 24 and is connected to a weight 25 to return the pressure member to its original position after the treadle is released thereby returning the treadle also.

To the rear of the pressure devices, on the table of the machine, is hinged at 26 the plate 27. This plate has journals 28, 28, for the pintle 29 of a roller 30, and the plate is pressed upwardly by a spring 31. Extending out beneath the pressure member from this spring mounting for the roller is a raised toe shaped rest 32 for the toe of the last to be acted upon, and the spring roller is adapted for forming a flexible rest for 90 the under side of the heel of the last, while the toe is held rigidly on the said toe rest.

Mounted pivotally on a pair of arms 33, extending up at either side of the roller mount, is a rod 34 on which is mounted the 10 top retaining plate 35. This plate has on its under side the post 36 for engagement in the usual hole in the last, and the plate is under the tension of a flat spring 37 which tends to hold it in position against the upper side of the heel of a last.

The last retaining members above described are all mounted on a sliding bed 38 which slides on angle iron guides 39 on each side of the table behind the pressure 11 members. The last is inserted in the holding devices by placing the heel portion over the spring roller, and lowering the plate 35 so that the post enters the hole in the last. The last is then resiliently held at the heel 11 and its toe rests on the toe rest 32.

A transversely sliding bar 40 is provided controlled by a handle 41, which is pivoted to one end of and extends to the front of the machine. This bar has a series of steps 42 12 for different sized lasts and lies in the path of the sliding bed. The operator selects the proper abutment step for the last to be used, and then slides the bed rearward until it is stopped by the said step. The last will then 12 be positioned with its toe directly beneath the pressure foot, and the slight lateral adjustments, which are necessary for rights and lefts in many lasts, may be accomplished by moving the toe of the last slightly, the 13

mounting devices being loose enough to allow this movement.

It can be seen that the operation of the retaining devices is simple and will hold the

- 5 last so that it will not slip out of place during the pressing process. The rubber shoe will come down closely around the edges of the toe, and the pad 20 will press down in conformity to the curve of the top of the toe.
- 10 If the pad 20 were omitted, the rubber shoe could be made thick enough to serve the same purpose, it being necessary only that the pressure members should engage uniformly over the upper surface of the toe of
- 15 the last, and that they should conform to the shape of the last. The rubber could be omitted and the pressure shoe formed of canvas or some like material, but the rubber foot 18 is believed by me to be necessary in about the
- 20 form described.

It is desired to note particularly that this machine could readily be used for other purposes for box toes, such as molding box toe pieces over the last before inserting in

25 the shoe, and other kindred molding or pressing operations over the toes of shoe lasts.

Having thus described my invention, what I claim as new and desire to secure by Letters Patent, is:—

30 1. In a machine of the character described, a compressible member of elastic material to operate upon the upper side of the toe of a last, a flexible member on said compressible member, and means for pulling down said members over said toe.

2. In a machine of the character described, a compressible member composed of rubber or like material to operate upon the upper side of the toe of a last, and a flexible member about said compressible member, means for depressing the said compressible member, and means for engaging the edges of the flexible material and pulling it down over

45 the said toe.

3. In a machine of the character described,

a flexible member to lie over and entirely cover the toe of a last, and compressible means engaging around the edges thereof to pull the same down around the said toe, for the

50 purpose described.

4. In a machine of the character described, a compressible member, an actuating member therefor, a spring for operatively connecting said members, and means on the actuating member for engaging the edges of said compressible member without the intervention of the spring, to pull the edges thereof over the toe of a last, after the spring connection has gone into play so as to give them

55 60 an additional movement.

5. In a machine of the character described, the combination with means for holding a last, of a pressure member comprising a rubber member faced with non-elastic fabric,

65 and means for pressing said rubber against the toe of the last, said fabric being adapted to prevent over stretching of the rubber.

6. In a machine of the character described, the combination with means for holding a

70 last, of a pressure member comprising in part a series of pivoted claws, a pressure shoe formed of flexible material, and means on the claws for engaging the edges of the shoe to press it down over the toe of a last.

75

7. In combination with means for holding a last, a means for pressing a box toe over the last comprising a reciprocating head, a pressure shoe, means resiliently connecting the central portions of the shoe to the head

80 and additional means nonresiliently connecting the edges of the shoe to the head, for the purpose described.

8. In combination with means for holding a last, a means for pressing a box toe over the last comprising a reciprocating head, a pressure shoe, means resiliently connecting the central portions of the shoe to the head and a series of claw members pivoted to the head and secured to the edges of

85 90 the shoe, for the purpose described.

ALBERT J. RYAN.
